Primary Examiner — Angela J Lee*Assistant Examiner* — Shawn T Gingrich(74) *Attorney, Agent, or Firm* — Dilworth & Barrese, LLP(57) **CLAIM**

The ornamental design for an electric connector, as shown and described.

DESCRIPTION

FIG. 1 is front elevational view of a first embodiment of an electric connector showing my new design;
 FIG. 2 is a rear elevational view thereof;
 FIG. 3 is a left side elevational view thereof;
 FIG. 4 is a right side elevational view thereof;
 FIG. 5 is a top plan view thereof;
 FIG. 6 is a bottom plan view thereof;
 FIG. 7 is a front, left side, top perspective view thereof; and,
 FIG. 8 is a rear, right side, top perspective view thereof.
 The broken lines showing of the electric connector is for the purpose of illustrating portions of the electric connector and forms no part of the claimed design.
 The dot-dash broken lines define the boundaries of the claimed design and form no part of the claimed design.
